CYLINDER HEAD FOR INTERNAL COMBUSTION ENGINES

Enrico Pateras Pescara, Cap d'Antibes, France

Application August 1, 1947, Serial No. 765,566
In Spain June 10, 1943Section 1, Public Law 690, August 8, 1946
Patent expires June 10, 1963

9 Claims. (Cl. 123—90)

1

The present invention relates to the cylinder heads of internal combustion engines and more especially to those which are provided, in their end walls, with the seats of two distribution valves actuated from a single cam-shaft, these engines being further characterized in that the stems of said valves, located approximately in a transverse plane with respect to the axis of the engine are suitably inclined (or at least one of them is inclined) with respect to the axis of the corresponding cylinder, with a view to obtaining large section distribution orifices.

My invention is applicable both to engines made especially according to the features of said invention, and to engines of any existing type (explosion engines, Diesel engines, engines having their valves housed in the cylinder head, in the cylinder block, having their valve system operated by a cam-shaft housed in the crank-case or in the cylinder head, engines fed with gasoline, with gas-oil, with gas, etc.), the existing cylinder heads being in this case replaced by others made according to my invention.

The chief object of my invention, while ensuring a certain reduction of weight, volume and cost of said cylinder heads, is to increase the maximum specific power compatible with the general constructional arrangements that are conventionally employed in industry.

It consists chiefly in the combination, in the same cylinder head, of the three following characteristics:

a. In the part corresponding to the valves, to their control mechanism and to the pipes, the cylinder head is made according to the usual standards of construction for engines having their valves disposed in the cylinder head and operated from a single cam-shaft, that is to say having an upper cooling water jacket around the seats of said valves, their guides and the pipes, the valve control mechanism being protected by a cover fixed to the cylinder head;

b. In the other regions, the cylinder head is of lower height than in said part and has the other characteristics of the conventional construction cylinder heads of engines having their valves disposed laterally in the cylinder-block, this cylinder head being not fitted with a cover in said regions;

c. The ignition plug or plugs are located wholly on the outside of the cylinder head cover and inside the region of lower height mentioned in paragraph (b), and open into the upper wall of the combustion chamber, near the center thereof, preferably in an optimum position which

2

reduces to a minimum the path of travel of the flame during the ignition period and which proves to be very advantageous, both concerning accessibility to said plugs and the cooling thereof. The arrangement of said low height region is further characterized in that, on the one hand, it covers at least partly the combustion chambers of the cylinder head and, on the other hand, it communicates with the outside through a discharge orifice or channel of a shape such that water, oil, or any other liquid as may have entered thereinto, flow out freely.

In addition to this main feature, my invention may include the following other features to be used either together or separately.

When double ignition is provided, in engines including one or several groups of cylinders in line, with two overhead valves having their axes in a transverse plane, the two ignition plugs of each cylinder are located symmetrically with respect to the axis of the combustion chamber and also with respect to said transverse plane of the two valves, which permits of obtaining a perfect synchronizing, both from a geometrical and a thermal point of view in the propagation of flame from these sparking plugs.

In order further to improve the position of the ignition plug or plugs, their axes are given an inclination such that the body of the plug is distant from the inlet and exhaust pipes, while, on the contrary, the ends of their electrodes are located as close as possible to the center of the combustion chamber.

And, in the case of an engine having a double ignition, I make use, for transmission of the cam-shaft drive to the inlet valve, of a bent rocker device, constituted by two levers fixed to each other, and one of which receives the thrust from the cam while the other transmits this thrust to said valve, the second of said levers being located in a plane perpendicular to the plane that contains the axes of the two ignition plugs and being approximately midway between these two axes.

Preferred embodiments of my invention will be hereinafter described with reference to the accompanying drawings, given merely by way of example and in which:

Fig. 1 is an elevational view, partly in section, of a cylinder head for a block of two cylinders in line, according to my invention;

Fig. 2 is a cross sectional view on the line 2—2 of Fig. 3;

Fig. 3 is a top plan view of the structure of Fig. 55 1, with the cover of the cylinder head removed;

Fig. 4 is a bottom plan view of the structure of Fig. 1;

Fig. 5 shows, in vertical section on the line 5—5 of Fig. 6 (the rocker arm system being not in section) another embodiment of a cylinder head made according to my invention;

Fig. 6 is a plan view of the cylinder head of Fig. 5 with the cover removed.

In the embodiment of Figs. 1 to 4, I have shown two cylinders 10 and 11, a plane wall 12 being adapted to receive the cylinder head gasket 13. I associate with each of these cylinders (cylinder 10 being taken by way of example) a combustion chamber such as 14 in the top wall of which are located the seat of an inlet valve 15 the axis of which is inclined with respect to cylinder 10 and the seat of an exhaust valve 16 the axis of which is approximately parallel to that of cylinder 10, these valve axes being disposed substantially in a transverse plane with respect to the axis of the engine.

The movements of valve 15 are controlled from a cam shaft C, mounted for instance in the crank-case, through a rod 17 which actuates a bent rocker device pivoted on a spindle 20 common to the control devices of both of the cylinders 10 and 11 and which will be more explicitly referred to hereinafter.

The opening and closing of exhaust valve 16 are ensured, from the same cam-shaft C that controls valve 15, through rod 19 and rocker means 24 pivoted on a spindle 21.

In cylinder 11, the parts of the control mechanism are identical to and symmetrical with those above described, and they are designated on the drawings by the same reference numerals increased by 100 (rod 117, 119, rocker arm 124, etc.).

The ignition plugs of chamber 14 that correspond to cylinder 10 are located at 22, 23 in the case of double ignition, and only one of them is provided in the case of a simple ignition.

As it can be seen from the drawings, said plugs 22, 23, the axes of which are advantageously inclined, open into the upper wall of combustion chamber 14 between the seats of valves 15 and 16 and in the vicinity of the center of this chamber.

The above mentioned inlet rocker device includes a lever 36, actuated by rod 17, a sleeve 37 journalled on spindle 20 and another lever 18 which actuates inlet valve 15. It should be noted that said lever 18 is located in a plane perpendicular to that determined by the axes of plugs 22 and 23 and is at equal distance between them.

An identical arrangement is used for cylinder 11, where the ignition plugs are 122, 123 and the inlet rocker arm 136, 137, 118.

The valve control mechanism constituted by the above indicated parts and in particular by the four rocker means 36—37—18, 136—137—118, 24 and 124 and their spindles 20, 21 and 121 are protected by a common cover 25 of particular shape which covers all the part of the cylinder head that includes valves 15, 115, 16, 116, their control means 17, 117, 19, 119, 36—37—18, 136—137—118, 24, 124, inlet pipes 27, 127, exhaust pipes such as 28 and, generally speaking, all the water jacket 29 that surrounds the valve guides, such as 30 and 31 and springs 32, 132, and 33, 133.

The gasket 26 of cover 25 first passes around the sparking plug 22 of cylinder 10, then around the spring 32 of valve 15 and around the second plug 23, following the same outline around the corresponding parts located above cylinder 11.

Between inlet pipes 27, 127 there is left a free interval 50.

Thus, the non-covered portion of the cylinder head, i. e. that on the outside of cover 25 includes:

1. On the right and on the left of this cover, two regions 34, 134 in which the sparking plugs 22, 122 are screwed,
2. At the center, a region 35 in which are screwed sparking plugs 23, 123.

This non-covered portion of the cylinder head, including said regions 34, 134, 35, which extends as far as one side wall of the cylinder block, has its top face at a level lower than the portion located under cover 25, which corresponds to water jacket 29. Consequently, region 35 constitutes a hollow in the top face of the cylinder head. But water, oil, or any other liquid as may have entered this hollow, is allowed to flow out through interval 50, which extends down to the level of the bottom of hollow 35.

Of course, the construction which has just been described in the case of two cylinders in line such as 10, 11, may be repeated twice, thrice and as much as four times, according as the engine includes four, six or eight cylinders. I would thus provide a number of elementary cylinder heads equal to the number of pairs of cylinders in the engine. But such an arrangement, which consists in treating two by two the adjacent cylinders and which may have advantages in certain cases, for instance in engines of large unitary cylinder capacity, must not be considered as an essential feature of my invention since, as it will be easily understood, the latter might as well be applied to engines having more than four cylinders in line with a single cylinder head or at least a cylinder head divided in a manner suitably adapted to the division of the cylinder head cover.

If, for instance, it is desired to provide a cylinder head for an engine having four cylinders in line, I make for instance use of the arrangement of Figs. 5 and 6.

The various parts to be included in the cylinder head having been sufficiently described above, it suffices now to indicate the chief pieces of this new assembly, to wit: the cylinders (only two of which, 210 and 211 are shown), the plane wall 212 for gasket 213, the combustion chambers 214 and 314, the inlet valves 315, the exhaust valves 316, the control rods 217 and 317, the exhaust rocker arm axes 224 and 324, and the exhaust rocker support 221.

The combustion chamber, in this case, is provided with only one ignition plug 222, 322. The inlet valve rocker device is simple and constituted by a single lever 236, 336, sleeve 237, 337, being journalled on spindle 220 which is common to the group of two cylinders that is shown.

The cylinder head cover 225, of particular shape, surrounds, as in the above described example, the whole of the valve control parts and is common to the four cylinders of the engine, the part that is not shown being symmetrical with respect to the half that is visible on Fig. 6.

The gasket 226 of cover 225 passes first around the ignition plug 222 of cylinder 210, then around the spring 232 of the inlet valve of cylinder 210 and also around the springs of the successive inlet valves, such as the spring 332 that corresponds to valve 315 etc., as far as the end of the cylinder block (not shown).

Thence, the gasket in question passes around the springs of the various exhaust valves and the plugs corresponding to each cylinder.

In the central portion, it will be noted that this gasket 226 must pass around both plug 322 and plug 422, thus forming a chamber closed over

its whole periphery, with the exception of a passage corresponding to a kind of outlet channel 250.

After plug 322, which corresponds to cylinder 211, the gasket finishes its circuit by passing around the springs of the exhaust valves.

In this way, there remains on the outside of cover 222:

1. On the right and on the left thereof, two regions of low height such as 234 (the other one, which is symmetrical therewith being not shown) in which the plugs of the end cylinders such as 222 are screwed and,

2. In the central portion, a region 235 in which are screwed the plugs 322 and 422 of the central cylinders, this last region communicating with the outside through discharge channel 250.

As, on the inside of the cylinder head, in all the portion thereof that corresponds to these regions 235, 234 and those symmetrical therewith and not shown, there is no part or conduit, the height of this cylinder head can be reduced in these regions to that of the water jacket necessary for the cooling of the combustion chambers that this jacket covers partly.

Such a construction further permits of reducing the weight and the volume of the cylinder head, while the plugs are located within easy reach, are well cooled and in the most adequate portion of the combustion chamber. This arrangement of the plugs permits of increasing to its maximum the specific power of engines, especially engines of large unitary cylinder capacity which have combustion chambers of large volume and also of poor thermal efficiency when the plug or plugs are disposed far from the positions corresponding to the minimum path of travel of the flame.

This advantage is further increased when these engines of large cylinder capacity are intended to be fed with a gas the combustion of which is very slow.

It will be further understood that, in the case of double ignition, the symmetrical position of the two plugs permits of ensuring a better synchronization of the propagation of the flames that are produced at each of these plugs. This result is particularly interesting since, when synchronization is not ensured, double ignition gives no advantage and, on the contrary, involves many drawbacks.

In engines including one or several groups of cylinders in line, it seems possible, at first sight, to obtain an apparent symmetry when the valves are disposed transversely to the axis of the engine, by placing a plug at either end of the transverse line extending between these valves.

But, in point of fact, this symmetry is only a geometrical one because the thermal conditions vary considerably from the region of the combustion chamber that corresponds to the exhaust valve to the much cooler region around the inlet valve, and, on the other hand, it is not possible to place the plugs in the lateral wall located between two consecutive cylinders of a group of cylinders in line.

It follows that, in engines of the kind in question, the only solution for complying both with geometrical symmetry and with thermal symmetry while remaining inside acceptable conditions of accessibility and cooling, is the solution given by the present invention.

However, the above described arrangement of the plugs is not to be mistaken for the one, already known in the art, which consists in having said ignition means opening into the upper

wall of the combustion chamber and in locating them in the cylinder head which further contains the valve seats because, according to this known arrangement, the plugs are disposed at the bottom of a tube which extends, over its whole height, through the cylinder head cover, which tube also acts eventually as a means for fixing or removing these plugs, in view of the great difficulty of reaching them.

10 1) Independently of this drawback, this known arrangement has many others: multiplicity of oil leaks, bad cooling, difficult insulation and therefore necessity of costly and little reliable devices, etc., to which drawbacks the invention remedies fully.

15 Finally, it should also be noted that the inclination of the plug or plugs with respect to each other permits of further improving their position in the combustion chamber by placing them closer to the center of the latter, while it renders the machining of the cylinder head easier.

20 In a general manner, while I have, in the above description, disclosed what I deem to be practical and efficient embodiments of my invention, it should be well understood that I do not wish to be limited thereto as there might be changes made in the arrangements, disposition and form of the parts without departing from the principle of 25 the present invention as comprehended within the scope of the accompanying claims.

What I claim is:

30 1. In an internal combustion engine including a block of at least two cylinders in line, a cylinder head forming a combustion chamber for each of said cylinders, the top walls of each of said chambers being provided with an inlet valve seat and an exhaust valve seat, an inlet valve and an exhaust valve adapted to cooperate with said 35 seats, respectively, the stems of said two valves being located in a plane perpendicular to the plane of the axes of said cylinders and at least one of these two stems being inclined with respect to the axis of the corresponding cylinder, inlet and exhaust pipes leading to said seats, respectively, rocker arm means located above said cylinder head for operating said valves, means located wholly on one side of the plane passing through the axes of said cylinders for driving 40 said rocker arm means, a cover for protecting said rocker arm means carried by said cylinder head extending exclusively over the portion thereof corresponding to said valves, said rocker arm means and said driving means, the non-covered portions of said cylinder head being of lower 45 height than the portion thereof fitted with said cover and extending as far as the side wall of said cylinder block located on the other side of the plane of the cylinder axes from said driving means, and at least one ignition plug mounted in said non-covered portions of the cylinder head 50 and opening into said combustion chamber near the center thereof.

55 2. In an internal combustion engine including a block of at least two cylinders in line, a cylinder head forming a combustion chamber for each of said cylinders, the top walls of each of said chambers being provided with an inlet valve seat and an exhaust valve seat, an inlet valve and an exhaust valve adapted to cooperate with said 60 seats, respectively, the stems of said two valves being located in a plane perpendicular to the plane of the axes of said cylinders and at least one of these two stems being inclined with respect to the axis of the corresponding cylinder,

inlet and exhaust pipes leading to said seats, respectively, rocker arm means located above said cylinder head for operating said valves, means located wholly on one side of the plane passing through the axes of said cylinders for driving said rocker arm means, a cover for protecting said rocker arm means carried by said cylinder head extending exclusively over the portion thereof corresponding to said valves, said rocker arm means and said driving means, the non-covered portions of said cylinder head being of lower height than the portion thereof fitted with said cover and extending as far as the side wall of said cylinder block located on the other side of the plane of the cylinder axes from said driving means, and two ignition plugs for each cylinder mounted in said non-covered portions of the cylinder head so as to open into said combustion chamber near the center thereof, said plugs being disposed symmetrically with respect both to the axis of said cylinder and to the transverse plane of the stems of the two valves of said cylinder.

3. In an internal combustion engine including a block of at least two cylinders in line, a cylinder head forming a combustion chamber for each of said cylinders, the top walls of each of said chambers being provided with an inlet valve seat and an exhaust valve seat, an inlet valve and an exhaust valve adapted to cooperate with said seats, respectively, the stems of said two valves being located in a plane perpendicular to the plane of the axes of said cylinders and at least one of these two stems being inclined with respect to the axis of the corresponding cylinder, inlet and exhaust pipes leading to said seats, respectively, rocker arm means located above said cylinder head for operating said valves, means located wholly on one side of the plane passing through the axes of said cylinders for driving said rocker arm means, a cover for protecting said rocker arm means carried by said cylinder head extending exclusively over the portion thereof corresponding to said valves, said rocker arm means and said driving means, the non-covered portions of said cylinder head being of lower height than the portion thereof fitted with said cover and extending as far as the side wall of said cylinder block located on the other side of the plane of the cylinder axes from said driving means, and at least one ignition plug mounted in said non-covered portions of the cylinder head and opening into said combustion chamber near the center thereof, said plug having its axis inclined with respect to the corresponding cylinder axis so as to have the plug body at the maximum distance from said pipes and its electrode close to the center of the combustion chamber.

4. In an internal combustion engine including a block of at least two cylinders in line, a cylinder head forming a combustion chamber for each of said cylinders, the top walls of each of said chambers being provided with an inlet valve seat and an exhaust valve seat, an inlet valve and an exhaust valve adapted to cooperate with said seats, respectively, the stems of said two valves being located in a plane perpendicular to the plane of the axes of said cylinders and at least one of these two stems being inclined with respect to the axis of the corresponding cylinder, inlet and exhaust pipes leading to said seats, respectively, rocker arm means located above said cylinder head for operating said valves, means located wholly on one side of the plane passing through the axes of said cylinders for driving said rocker arm means, a cover for protecting said

rocker arm means carried by said cylinder head extending exclusively over the portion thereof corresponding to said valves, said rocker arm means and said driving means, the non-covered portions of said cylinder head being of lower height than the portion thereof fitted with said cover and extending as far as the side wall of said cylinder block located on the other side of the plane of the cylinder axes from said driving means, and two ignition plugs for each cylinder mounted in said non-covered portions of the cylinder head so as to open into said combustion chamber near the center thereof, said plugs being disposed symmetrically with respect both to the axis of said cylinder and to the transverse plane of the stems of the two valves of said cylinder, said plugs having their axes inclined with respect to the corresponding cylinder axis so as to have each plug body at the maximum distance from said pipes and its electrode close to the center of the combustion chamber.

5. In an internal combustion engine including a block of at least two cylinders in line, a cylinder head forming a combustion chamber for each of said cylinders, the top walls of each of said chambers being provided with an inlet valve seat and an exhaust valve seat, an inlet valve and an exhaust valve adapted to cooperate with said seats, respectively, the stems of said two valves being located in a plane perpendicular to the plane of the axes of said cylinders and at least one of these two stems being inclined with respect to the axis of the corresponding cylinder, inlet and exhaust pipes leading to said seats, respectively, means located above said cylinder head for operating said valves, a cover carried by said cylinder head extending exclusively over the portion thereof corresponding to said valves and said valve operating means, the non-covered portions of said cylinder head being of lower height than the portion thereof fitted with said cover and extending as far as one side wall of said cylinder block, two ignition plugs for each cylinder mounted in said non-covered portions of the cylinder head so as to open into said combustion chamber near the center thereof, said plugs being disposed symmetrically with respect both to the axis of said cylinder and to the transverse plane of the stems of the two valves of said cylinder, a single cam-shaft for driving said valve operating means located on one side of the plane passing through the axes of said cylinders, said valve operating means including a part pivoted to said cylinder head about an axis perpendicular to the transverse planes containing each the stems of the two valves of each cylinder, two rocker arm elements rigid with said part, operatively connected with said cam-shaft respectively, and two rocker arm elements, also rigid with said part and at right angles to the pivot axis thereof adapted to cooperate each with the inlet valve of one of said two cylinders respectively for controlling it, said second mentioned rocker arm elements being each located at mid-distance from the axes of the ignition plugs of the corresponding cylinder.

6. In an internal combustion engine including a block of at least two cylinders in line, a cylinder head forming a combustion chamber for each of said cylinders, the top walls of each of said chambers being provided with an inlet valve seat and an exhaust valve seat, an inlet valve and an exhaust valve adapted to cooperate with said seats, respectively, the stems of said two valves being located in a plane perpendicular to the

plane of the axes of said cylinders and at least one of these two stems being inclined with respect to the axis of the corresponding cylinder, inlet and exhaust pipes leading to said seats, respectively, means located above said cylinder head for operating said valves, a cover carried by said cylinder head extending exclusively over the portion thereof corresponding to said valves and said valve operating means, the non-covered portions of said cylinder head being of lower height than the portion thereof fitted with said cover and extending as far as one side wall of said cylinder block, two ignition plugs for each cylinder mounted in said non-covered portions of the cylinder head so as to open into said combustion chamber near the center thereof, said plugs being disposed symmetrically with respect both to the axis of said cylinder and to the transverse plane of the stems of the two valves of said cylinder, said plugs having their axes inclined with respect to the corresponding cylinder axis so as to have each plug body at the maximum distance from said pipes and its electrode close to the center of the combustion chamber, a single cam-shaft for driving said valve operating means located on one side of the plane passing through the axes of said cylinders, said valve operating means including a part pivoted to said cylinder head about an axis perpendicular to the transverse planes containing each the stems of the two valves of each cylinder, two rocker arm elements rigid with said part, operatively connected with said cam-shaft respectively, and two rocker arm elements, also rigid with said part and at right angles to the pivot axis thereof adapted to cooperate each with the inlet valve of one of said two cylinders respectively for controlling it, said second mentioned rocker arm elements being each located at mid-distance from the axes of the ignition plugs of the corresponding cylinder.

7. In an internal combustion engine including a block of at least two cylinders in line, a cylinder head forming a combustion chamber for each of said cylinders, the top walls of each of said chambers being provided with an inlet valve seat and an exhaust valve seat, an inlet valve and an exhaust valve adapted to cooperate with said seats, respectively, the stems of said two valves being located in a plane perpendicular to the plane of the axes of said cylinders and at least one of these two stems being inclined with respect to the axis of the corresponding cylinder, rocker arm means located above said cylinder head for operating said valves, means located wholly on one side of the plane passing through the axes of said cylinders for driving all of said valve operating means, inlet and exhaust pipes leading to said seats, respectively, cooling water jacket means surrounding said valve seats and said pipes included in said cylinder, a cover for protecting said rocker arm means carried by said cylinder head extending exclusively over the portion thereof corresponding to said valves, said rocker arm means and said driving means, the non-covered portions of said cylinder head being of lower height than the portion thereof fitted with said cover and extending as far as the side wall of said cylinder block located on the other side of the plane of the cylinder axes from said driving means, and at least one ignition plug mounted in said non-covered portions of the cylinder head and opening into said combustion chamber near the center thereof.

8. In an internal combustion engine including a block of at least two cylinders in line, a cylin-

der head forming a combustion chamber for each of said cylinders, the top walls of each of said chambers being provided with an inlet valve seat and an exhaust valve seat, an inlet valve and an exhaust valve adapted to cooperate with said seats, respectively, the stems of said two valves being located in a plane perpendicular to the plane of the axes of said cylinders and at least one of these two stems being inclined with respect to the axis of the corresponding cylinder, inlet and exhaust pipes leading to said seats, respectively, rocker arm means located above said cylinder head for operating said valves, means located wholly on one side of the plane passing through the axes of said cylinders for driving said rocker arm means, a cover for protecting said rocker arm means carried by said cylinder head extending exclusively over the portion thereof corresponding to said valves, said rocker arm means and said driving means, the non-covered portions of said cylinder head being of lower height than the portion thereof fitted with said cover and extending as far as one side wall of said cylinder block, and at least one ignition plug mounted in said non-covered portions of the cylinder head and opening into said combustion chamber near the center thereof.

9. In an internal combustion engine, a block of at least two cylinders in line, a cylinder head forming a combustion chamber for each of said cylinders, the top walls of each of said chambers being provided with an inlet valve seat and an exhaust valve seat, an inlet valve and an exhaust valve adapted to cooperate with said seats, respectively, the stems of said two valves being located in a plane perpendicular to the plane of the axes of said cylinders and at least one of these two stems being inclined with respect to the axis of the corresponding cylinder, rocker arm means located above said cylinder head for operating said valves, means located wholly on one side of the plane passing through the axes of said cylinders for driving all of said valve operating means, inlet and exhaust pipes leading to said seats, respectively, cooling water jacket means surrounding said valve seats and said pipes included in said cylinder, a cover for protecting said rocker arm means carried by said cylinder head extending exclusively over the portion thereof corresponding to said valves, said rocker arm means and said driving means, the non-covered portions of said cylinder head being of lower height than the portion thereof fitted with said cover and extending as far as one side wall of said cylinder block, and at least one ignition plug mounted in said non-covered portions of the cylinder head and opening into said combustion chamber near the center thereof.
